ROTARY TYPE AIR COMPRESSOR

Daniel F. McGill, Portland, Oreg.

Application October 30, 1943, Serial No. 508,369

13 Claims. (Cl. 230—152)

1

This invention relates to new and useful improvements in rotary type air compressors.

It is the primary object of the invention to provide an air compressor having means for creating an expansion of air in the fluid chambers of the device for cooling the device.

It is a further object of the invention to provide in an air compressor means for introducing air under pressure into the fluid chambers during travel thereof between suction and discharge sides of the pump in an amount sufficient to equalize the pressure between said fluid chambers and the compressed air tank.

It is a further object of the invention to provide in an air compressor means for circulating water for sealing purposes through the compressor under equal or greater pressure than the air pressure created by operation of the device.

It is a further object of the invention to provide an air compressor capable of producing cool, dry air.

It is a further object of the invention to provide in a rotary type air compressor means for withdrawing the rotor vanes from operative position during periods of inoperation of the compressor so as to unload the prime mover at time of starting.

It is a further object of the invention to provide an air compressor of the rotary type in which the rotor vanes may be moved to inoperative position during rotation of the rotor to avoid the necessity of stopping and starting the motor between periods of operation.

The invention comprises a rotor mounted within an elliptical chamber wherein the wall of the chamber between the intake and discharge ports is concentric with the rotor. Rotor vanes are arranged at intervals around the rotor, which, together with the rotor and chamber wall, define a plurality of fluid chambers arranged for travel from the suction to the discharge sides of the pump. The vanes are so mounted in the rotor that each vane may move in and out of the rotor independently of the other vanes. The vanes are inclined forwardly in relation to the direction of rotation and are moved into engagement with the wall of the chamber by the pressure of lubricating and sealing liquid admitted to passages at the inner ends of the rotor vanes.

The sealing liquid may be led from the delivery side of the pump, or from a tank in which said liquid is subjected to the pressure developed by the pump, into passages at the inner ends of the rotor vanes to force them outwardly. In the preferred embodiment of the invention such liquid

2

is circulated through the compressor and back to the tank by means of a centrifugal type pump attached to the rotor. By means of a pressure regulating valve in the return pipe line the sealing and lubricating fluid may be utilized at a slightly higher pressure than that present in the aforementioned tank.

Another feature of the invention resides in the provision of an apparatus for introducing compressed air into the fluid chambers in the compressor during their travel between suction and discharge sides of the pump. As the compressed air passes into said chambers it is expanded therewithin and is cooled by reason of its release from pressure, and in so doing absorbs the heat created by friction of the moving parts of the pump.

These and other desired objects and advantages of the invention are obtained through the novel arrangement, the unique construction, and the improved combination of the various parts hereinafter described in conjunction with the accompanying drawings, it being understood that various changes in form, proportion, size and details of construction within the scope of the claims may be resorted to without departing from the spirit or sacrificing any of the advantages of the invention.

In the drawings: Figure 1 is a longitudinal sectional view of an air compressor embodying the invention; Figure 2 is a transverse section of the air compressor, taken on the line 2—2 of Figure 1 and including a diagrammatic sectional view of the tank and its related piping; Figure 3 is a longitudinal sectional view taken on the line 3—3 of Figure 1; Figure 4 is a diagrammatic drawing showing the development of the interior of the casing of the structure shown in Figures 1 and 2; and Figure 5 is a side elevation of an apparatus illustrating the principle of operation of the invention.

In the illustrated embodiment of the invention the rotor 10 is mounted within a casing 11 having heads 12 and 13, respectively, defining a pump chamber 14. The inner peripheral wall of the casing 11 is preferably elliptical, the axis about which the rotor 10 rotates being concentric with diametrically opposite portions of the casing wall. The contour of the one side of the casing wall may be described as a circular arc A—B subtending an angle Z about a center R which is coincident with the center of the rotor 10. The opposite wall of the chamber is described as a circular arc C—D subtending an angle Y about a center S, which is spaced from the center R along the vertical axis of the chamber 14 by an

amount equal to the distance from the periphery of the rotor 10 to the surface of the wall on the arc A—B.

An arcuate recess in the casing wall defined by the arc C—D is described by rotating a line E—F through the angle V about the center R. The arcuate recess E—F coacts with the rotor 10 to provide an extended sealing area between the suction and discharge sides of the pump. At the ends of the ellipse formed by the arcs A—B and C—D the walls of the chamber may be described by rotating lines M—N through the angles O about centers T. The arcs M—N and E—F intersect the arcs A—B and C—D tangentially with no sudden changes in direction, so that rapid changes in rate of movement of the rotor vanes are avoided. Between the points M—M on the arc A—B, the wall of the chamber 14 is coaxial with the rotor 10. The points M, M define the termini of oppositely disposed inlet and discharge ports 15 and 16, respectively, and hence the fluid chambers between adjacent rotor vanes do not vary in size during their travel between suction and discharge sides of the pump.

In the device illustrated in the drawings, angles Y and Z are equal and the radius K of the arc A—B is equal to the radius K' of the arc C—D. It will be appreciated, however, that either of the angles Z or Y may be lengthened or shortened relative to the other according to the use to be made of the device, and that the radii of the respective arcs will be lengthened and shortened proportionately.

The inlet port opening 15 extends, in the direction of rotation, from the point E to point M, and the discharge port opening 16 extends from point M to point F. At the points E and F the vanes do not project from the rotor. By extending the discharge port opening to the point F fluid cannot be trapped ahead of each vane which, if no slippage or leakage were present, would operate to stop the pump.

The rotor 10 is provided with slots 17 extending in a direction inclined forwardly from the radius 18 of the rotor, the slots being inclined forwardly in relation to the direction of rotation. The slots 17 extend through the rotor from one side to the other and terminate at their inner ends in passages 19 which communicate with the discharge or a centrifugal pump hereinafter more specifically described. The slots 17 form bearings in which vanes 21 are slidably mounted. The outer ends of the vanes are beveled to conform as nearly as possible with the general contour of the inner wall of the casing 11. By reason of the fact that throughout the arc A—B the casing wall is coaxial with the rotor 10, there is no relative movement between the vanes and the rotor while the vanes are under load. The vanes are so inclined relative to the radius 18 that when moving in the slot 17 the vanes tend to move in the plane of their longitudinal axes rather than at an angle thereto. As each vane travels through the arc M—F the convergence of the casing wall and the rotor compels the vane to move into the slot 17. Friction between the casing wall and the end of the vane tends to move the vane in a direction counter to the direction of rotation. Pressure on the end of the vane tends to move the vane in a radial direction, so that the force vector is disposed in a direction substantially parallel with the slot 17. While a lesser number of vanes than illustrated may successfully be employed, the structure shown provides a greater number of fluid chambers between the intake and

discharge ports, and insures the presence of at least one vane in the sealing area E—F between suction and discharge sides of the pump.

A pipe line 37 leads from the discharge port 16 to a pipe connection 38 in the bottom of a tank 39 which may preferably be positioned at an elevation above the pump. Mounted within the tank 39 so as to form therewith an inclosure for the end of the pipe line 37 is a baffle 41 having perforations 42 providing communication with the interior of the tank. It is intended that the tank 39 shall contain an amount of water sufficient to submerge both the baffle 41 and a screen 43 mounted in the lower portion of the tank above the baffle. The baffle 41 serves to diffuse the air entering the tank 39 over the bottom of the screen 43, which functions to break the air stream into small bubbles and separate out dirt and similar foreign matter carried by the air stream. A pipe connection 44 in the upper part of the tank 39 connects with the supply line 45 which leads from the tank to a place of use of the compressed air.

The rotor 10 is keyed to a shaft 22 journaled in bearings 23, 23 carried in the heads 12 and 13. Each head is provided with a stuffing box 24 having the usual packing members 25.

The head 13 is provided with an annular recess 26 and mounted within this recess is a centrifugal pump element 27. The centrifugal pump may comprise a circular disc 28 secured to the rotor 10 by means of screws 29. An axial flange 31 supports the disc 28 in spaced apart relation to the side wall of the rotor to cause the disc 28 to overlie the plate 32 forming the closure member for the adjacent end of the chamber 14.

The circular disc 28 is interrupted adjacent the shaft 22 to provide an intake or eye 33 from which fluid is supplied to passages 34 extending radially through the disc 28. The passages 34 discharge into the volute area 35 from whence liquid flows through a passage between the plate 32 and the circular disc 28 to an annular chamber 36 having communication with each of the passages 19 at the inner ends of the slots 17.

A pipe line 46 leads from a submerged portion of the tank 39 to a threaded connection 47 in the head 13 by means of which water is supplied to an annular chamber 48 in the head 13 communicating with the intake 33 of the centrifugal pump 27. The pipe line 49 leads from an annular chamber 51 in the head 12 to the tank 39. The pipe line 46 connects with the tank 39 at a point adjacent the bottom of the tank to insure a continuous flow of liquid to the centrifugal pump 27. The water circulated through the rotor carries therewith any dirt which may collect in the several passages associated with the centrifugal pump and rotor, and pipe line 49 may preferably be connected into the tank 39 at a point below the water level.

It will be appreciated that the water in the lower portion of tank 39 is under the pressure created by compression of the air in the tank. Operation of the centrifugal pump tends to circulate the water from the tank through the passages 19 at the inner ends of the slots 17, along the side walls between the rotor and housing, and into the annular chamber 51 in the head 12 on the opposite side of the rotor. From thence the water is returned by pipe line 49 to the tank 39. A pressure regulating valve 59 in the pipe line 49 may be so adjusted that the water in the passages 19 is at a slightly higher pressure than the water in the tank 39. For example, assuming that the water in the tank 39 is under a working

pressure of one hundred pounds per square inch, the water entering the suction of the centrifugal pump is under pressure of one hundred pounds. The valve 59 may be adjusted to require a pressure of five pounds to operate the valve, thus insuring a water pressure in the passages 19 somewhat greater than the air pressure. By circulating the water through and around the rotor structure in the compressor, leakage of air from the compressor is precluded, regardless of the pressure developed.

The angle of inclination of the vanes 21 is such that the inertia of each vane tends to hold the vane within the body of the rotor 10, and to require the application of some external force to move the vanes into engagement with the casing wall. This force is supplied through operation of the centrifugal pump 27, which coacts with the pressure regulating valve 59 to build up sufficient pressure in the passages 19 to move the vanes outwardly of the slots 17 and into engagement with the casing wall. A pipe line 64 extends between the return line 49 and the intake pipe 65, by means of which the water may be withdrawn from the passages 19 to permit the vanes 21 to remain wholly within the slots 17. With the vanes in such inoperative position, continuous operation of the rotor may be permitted without delivery of air to the tank 39 and without friction of vanes 21 on the casing wall. A valve 67 is provided to close the pipe line 64 during operation of the compressor. During periods of inoperation of the compressor, a check valve 66 prevents escape of air from the tank 39 by way of pipe line 37; a valve 68 is provided for closing the pipe line 46 to facilitate withdrawal of the water from passages 19 and so permit the vanes 21 to move to inoperative position; a valve 69 is provided for closing the pipe line 56; a valve 70 is provided for closing the pipe line 49; and valve 71 is operable to close the intake pipe 65. These valves may be interconnected for simultaneous operation by a master valve control mechanism (not shown) whenever the pressure in the tank is of a predetermined value. This arrangement of elements obviates the necessity of stopping the motor between periods of operation of the compressor.

A novel feature of the invention resides in the provision of means for admitting compressed air from the tank 39 into the chambers between adjacent rotor vanes 21 during the travel of such chambers from the suction to the discharge sides of the pump. It will be remembered that between the points M, M the capacity of these chambers is constant. A header 52 is arranged adjacent the casing 11, the header having communication with the chamber 14 by way of a plurality of nozzles 53a—b—c which are threaded into tapped orifices in the casing 11 at points spaced apart by a distance greater than the distance between adjacent rotor vanes 21. While the drawings illustrate the nozzles 53a—b—c as being threaded into the casing 11, it will be appreciated that the header 52 may be positioned adjacent the head 12 and that the nozzles 53 may be threaded into tapped orifices in the head. It is important, of course, that the orifices 54 be so positioned in either the casing 11 or the head 12 as to permit the nozzles 53 to discharge into successive fluid chambers between the rotor vanes 21. Each of the nozzles 53 is equipped with a valve 55 for regulating the flow from the header 52 through the nozzles 53. The header 52 is connected with the tank 39 by means of a pipe line 56

through which air from the tank 39 is supplied to the header 52.

In operation, air is admitted to the device by way of intake port 15 and is conveyed by way of chambers 57 between adjacent rotor vanes 21 to the discharge port 16 from whence it is conducted by way of pipe line 37 to the tank 39. For purposes of illustration, assuming that each chamber will contain one cubic foot of air at normal atmospheric pressure, in the structure as heretofore described the device will deliver one cubic foot of free air to the tank 39 as each successive fluid chamber in the casing 11 is moved into communication with the discharge port 16.

As the air enters the tank 39 through the pipe line 37 it is discharged through perforations 42 in the baffle 41 which tend to break up the air stream and distribute it over the bottom of the screen 43. As has been stated, the screen is submerged in water present in an amount sufficient to fill the tank to a level above the screen 43 so that the stream of air entering the tank through the baffle 41 and screen 43 is cleansed by the intimate association of the air and water as the air passes through the water in the form of small bubbles. From the tank 39 the air is supplied by way of supply line 45 to a place of use.

Air is also supplied from the tank 39 by way of pipe line 56 to the header 52 and from thence by way of nozzles 53a—b—c to the chambers 57. The first nozzle 53a is so positioned as to introduce air under pressure from the header 52 into the chamber 57a which has just been closed by the rotor vane 21a. The valve 55a in the nozzle 53a is so adjusted that a predetermined volume of air at the pressure existing in the tank 39 will flow through the nozzle in the period of time required for the passage of adjacent rotor vanes 21 past the nozzle orifice 54a. After the trailing rotor vane has passed over the orifice 54a of nozzle 53a, the leading rotor vane will have passed over the nozzle orifice of nozzle 53b, so that air is discharged into the chamber therethrough. The valve 55b in nozzle 53b is so adjusted as to admit into the chamber a predetermined volume of air at the pressure in the tank 39 within the period of time that the nozzle 53b is in communication with the chamber. After the trailing rotor vane 21 has passed over the orifice of nozzle 53b the leading rotor vane uncovers the orifice of nozzle 53c, whereupon air is introduced into the chamber therethrough. The valve 55c in nozzle 53c is so adjusted as to introduce into the chamber a predetermined volume of air at the pressure in the tank 39 within the period of time that the chamber is in communication with the nozzle 53c.

For purposes of clarifying the method of operation of the structure, Figure 5 shows a diagrammatic representation of a tank 61 containing air at one hundred pounds pressure. Adjacent tank 61 is a smaller tank 62 having a capacity of one cubic foot and containing air at atmospheric pressure. A pipe 63 connects the two tanks. With a given opening through pipe line 63 a certain length of time is required for equalization of pressure between the two tanks. As the air passes into the smaller tank 62 it will be cooled by reason of its release from pressure. The smaller tank 62 is representative of the fluid chamber 57 in an air compressor embodying the instant invention, and the time required for the travel of the chamber 57 from the suction to the discharge sides of the pump represents the time required to equalize the pressure be-

tween the tank 39 and the chamber. Initially each of the fluid chambers 57 is filled with air at atmospheric pressure and, assuming that the air in the tank 39 is under one hundred pounds pressure, air in an amount equal to approximately six cubic feet of free air is expanded into each of the chambers 57 and added to the one cubic foot of free air contained therewithin to equalize pressures between the chambers and the tank during the travel of each chamber between suction and discharge sides of the pump.

In a structure for handling large volumes of air it may be desired to introduce air into each fluid chamber 57 through a plurality of nozzles. For example, in an air compressor comprising a rotor 10 of considerable width, any desired number of nozzles 53 may be aligned transversely of the casing for introducing air into each successive fluid chamber. On the other hand, instead of employing nozzles spaced in the direction of travel of the fluid chamber, as herein illustrated and described, the desired cooling effect may be accomplished by the use of a single nozzle for ejecting air into each chamber passing the nozzle orifice. It should be understood, therefore, that the description of a particular arrangement of such nozzles is not to be considered in a limiting sense.

Having now described my invention and in what manner the same may be used, what I claim as new and desire to protect by Letters Patent is:

1. An air compressor comprising a casing substantially elliptical in cross section, inlet and outlet ports at opposite ends of said ellipse, a rotor journaled in said casing on an axis substantially concentric with one side of the ellipse between said ports, a plurality of vanes movably mounted inwardly and outwardly of the rotor to have tangential contact with the inner walls of the casing, said vanes, rotor and casing together forming a plurality of fluid chambers of constant capacity during travel between suction and discharge sides of the compressor, means for moving said chambers from the suction to the discharge sides of the compressor, a tank for receiving the air pumped by said compressor, and means for introducing air from said tank into said fluid chambers during travel thereof between suction and discharge sides of the compressor in an amount sufficient to equalize the pressure between said fluid chambers and said tank.

2. An air compressor comprising a casing, a rotor journaled in said casing on an axis substantially concentric with one wall of said casing, inlet and outlet ports in opposite wall portions of said casing, a plurality of vanes movably mounted inwardly and outwardly of the rotor to have tangential contact with the inner walls of the casing, said vanes, rotor and casing together forming a plurality of fluid chambers of constant capacity traveling from the suction to the discharge sides of the compressor as the rotor revolves in the casing, and means for introducing air under discharge pressure into a plurality of said fluid chambers in substantially all positions of said chambers during travel thereof between suction and discharge sides of the compressor to compress the original air in said chambers gradually.

3. An air compressor comprising a casing, inlet and outlet ports in opposite wall portions of said casing, a rotor journaled in said casing, a plurality of vanes mounted in said rotor, said

vanes, rotor and casing together forming a plurality of fluid chambers traveling between suction and discharge sides of the compressor, as the rotor revolves in the casing, a tank having a large volume relative to said chambers for receiving air discharged from said fluid chambers, and means for introducing air from said tank into said fluid chambers during travel thereof between suction and discharge sides of the compressor for equalizing the pressures in said tank and said fluid chambers.

4. A rotary pump comprising a casing, a rotor journaled in said casing, inlet and outlet ports in opposite portions of said casing, a plurality of vanes mounted in said rotor, said vanes, rotor and casing together forming a plurality of fluid chambers between the suction and discharge sides of said pump, a tank for receiving air discharged from said pump and constituting a source of supply of sealing liquid for said said compressor, means for expanding air under pressure from said tank into said fluid chambers in substantially all positions of said chambers between the suction and discharge ports in a sufficient volume to equalize the pressures in said tank and said fluid chambers during the time elapsed while each chamber is passing from suction to discharge sides of said pump, a pipe line from said tank for conducting said liquid to one side of said pump casing, a second pipe line returning from the opposite side of said pump to said tank, pump means for circulating said liquid from said tank through and around said rotor and through said pipe lines, and a pressure regulating valve in said second pipe line to control the pressure of said liquid in said casing whereby said liquid acts as a sealing means for said fluid chambers.

5. An air compressor comprising a casing, inlet and outlet ports in opposite wall portions of said casing, a rotor journaled in said casing, a plurality of vanes mounted in said rotor, said vanes, rotor and casing together forming a plurality of fluid chambers, means for moving said chambers from the suction to the discharge sides of the compressor, a tank for receiving the air discharged from said fluid chambers and constituting a source of supply of sealing and cooling water for said compressor, a water pump carried by said rotor capable of developing a water pressure in excess of the air pressure in said air compressor and tank for circulating said water from said tank through said rotor and between said rotor and said casing and back to said tank, and adjustable pressure regulator means for maintaining the pressure of said water while in said casing above the pressure in said tank by a predetermined differential.

6. An air compressor comprising a casing, inlet and outlet ports in opposite wall portions of said casing, a rotor journaled in said casing, a plurality of vanes mounted in said rotor, said vanes, rotor and casing together forming a plurality of fluid chambers, means for moving said chambers from the suction to the discharge sides of the compressor at constant volume, a tank for receiving the air discharged from said fluid chambers, a pipe line connecting said tank and said casing for returning air under discharge pressure to said casing, and nozzle means in said pipe to discharge said air into said chambers in substantially all positions of said chambers between suction and discharge sides of the compressor to establish discharge pressure in said chambers.

7. An air compressor comprising a casing having inlet and outlet parts, a rotor journaled in

said casing, a plurality of vanes movably mounted inwardly and outwardly of the rotor to have tangential contact with the inner walls of the casing, each said vane being inclined in a forward direction in relation to the direction of rotation of said rotor, said vanes tending to remain in retracted position within said rotor at normal operating speed due to the inertia of each vane, a passage extending through said rotor at the inner end of each said vane, means for admitting water under pressure through said passages for moving said vanes outwardly of said rotor and into engagement with the casing wall, pump means affixed to said rotor for circulating said water through said passages and adjustable pressure regulator means for maintaining the pressure of said water from said pump at a predetermined pressure differential above the pressure of the air discharged from said compressor.

8. An air compressor comprising a casing, inlet and outlet ports disposed in opposite wall portions of said casing, a rotor journaled in said casing, a plurality of vanes movably mounted inwardly and outwardly of the rotor to have tangential contact with the inner walls of the casing, each said vane being inclined in a forward direction in relation to the direction of rotation of said rotor whereby said vanes tend to be held in retracted position in said rotor at normal operating speed due to the inertia of each said vane, a passage extending through said rotor at the inner end of each said vane, means for admitting water under pressure into said passages behind the inner end of each vane to cause said vanes to move outwardly of said rotor and into engagement with the casing wall, conduit means connecting said passages and said inlet port whereby operation of said compressor may function to withdraw the water from said passages for permitting said vanes to move into retracted position in said rotor, and valve means in said conduit for controlling the flow of water therethrough.

9. An air compressor comprising a casing, inlet and outlet ports disposed in opposite wall portions of said casing, a rotor journaled in said casing, a plurality of vanes movably mounted inwardly and outwardly of the rotor to have tangential contact with the inner walls of the casing, each said vane being inclined in a forward direction in relation to the direction of rotation of said rotor whereby said vanes tend to remain in a retracted position in said rotor at normal operating speed due to the inertia of each said vane, a passage extending through said rotor at the inner end of each said vane, means for admitting water under pressure behind the inner end of each said vane to cause said vanes to move outwardly of said rotor and into engagement with the casing wall, and means for withdrawing the water from said passages for permitting said vanes to move into retracted position in said rotor.

10. An air compressor comprising a casing, inlet and outlet ports in opposite wall portions of said casing, a rotor journaled in said casing, a plurality of vanes movably mounted inwardly and outwardly of the rotor to have tangential contact with the inner walls of the casing, said vanes, rotor and casing together forming a plurality of fluid chambers movable between suction and discharge sides of the compressor, each said vane being inclined in a forward direction

in relation to the direction of rotation of said rotor whereby said vanes tend to remain in retracted position in said rotor at normal operating speed due to the inertia of said vanes, a tank for receiving air discharged from said fluid chambers and constituting a source of supply of water for said compressor, a passage extending through said rotor at the inner end of each said vane, conduit means connecting said passages and said tank for conducting water from said tank to said passages for moving said vanes outwardly of said rotor and into engagement with the casing wall.

11. An air compressor comprising a casing, inlet and outlet ports in opposite wall portions of said casing, a rotor journaled in said casing, a plurality of vanes movably mounted inwardly and outwardly of the rotor to have tangential contact with the inner walls of the casing, said vanes, rotor and casing together forming a plurality of fluid chambers movable between suction and discharge sides of the compressor, each said vane being inclined in a forward direction in relation to the direction of rotation of said rotor whereby said vanes tend to remain in retracted position in said rotor at normal operating speed due to the inertia of said vanes, a tank for receiving air discharged from said fluid chambers and constituting a source of supply of water for said compressor, a passage extending through said rotor at the inner end of each said vane, conduit means connecting said passages and said tank, pump means for circulating water from said tank through said passages and conduit means, a return pipe line connecting said passages and said tank, and a pressure regulating valve in said return pipe line, said pump means and said pressure regulating valve coacting to increase the pressure of water in said passages to a predetermined pressure differential in excess of the pressure existing in said tank.

12. An air compressor comprising a casing, inlet and outlet ports in opposite wall portions of said casing, a rotor journaled in said casing, a plurality of vanes mounted in said rotor, said vanes, rotor and casing together forming a plurality of fluid chambers between the suction and discharge sides of the compressor, a tank for receiving air discharged from said fluid chambers and constituting a source of supply of lubricating and sealing water for said compressor, pump means affixed to one side of said rotor for circulating water through and around said rotor, conduit means connecting said tank and said pump means, a return pipe line connecting said casing and said tank for returning said circulating water from said pump to said tank, and a pressure regulating valve in said return pipe line, said pump means and said pressure regulating valve coacting to maintain the water in said casing at a predetermined pressure differential above the air discharge pressure of the compressor.

13. An air compressor comprising a rotory vane type pump having vanes forming constant volume chambers movable between suction and discharge ports in the compressor, a tank connected with said discharge port to receive compressed air from said compressor, and a separate pipe from said tank to said pump for expanding air from said tank into said chambers in substantially all positions of said chambers as they move from said suction to said discharge ports and in a volume sufficient to cause the air pressure in the closed chamber nearest the discharge

11

port to equal the tank pressure whereby all the compression in said pump is produced by the expansion of air circulated from said tank.
